EUGENE MEMMLER, OF LOS ANGELES, CALIFORNIA

PRINTING PRESS GAUGE

Application filed April 5, 1932. Serial No. 603,292.

This invention relates to printing presses, and more particularly to the adjustment of the inking rollers to proper position for the proper inking of forms for printing.

5 An object of the invention is to provide a gauge which may be locked in the form with the type and thus held securely against the bed of the press in the same manner as the type, the gauge being provided with 10 impression surfaces of different heights on the top face so that when the printing press is put into motion the inking rollers will deposit ink on all the surfaces they come in contact with, whereby adjustment of the rollers may be made until an ink deposit is made 15 on those surfaces beginning with that particular surface bearing numerals indicating the preferred clearance between the bed of the press and the inking rollers to the end 20 that guess work in adjustment will be eliminated and poor inking entirely obviated.

A further object is to provide a gauge of the class described which will have a stepped top face providing impression surfaces, and 25 will have the impression surfaces separated by transversed grooves which perform the twofold function of separating the surfaces so that they will be more readily distinguished one from the other and also prevent 30 ink from collecting in the corners between the surfaces to the end that the surfaces will be constantly clearly and distinctly defined and their corresponding numerals, 35 preferably reading thousandths of an inch, easily read.

With the above and other objects in view the invention consists in certain novel details of construction and combinations of 40 parts hereinafter fully described and claimed it being understood that various modifications may be resorted to within the scope of the appended claims without departing from the spirit or sacrificing any of the advantages of the invention.

In the accompanying drawing forming part of this specification,

Figure 1 is a plan view of a printing press form equipped with a pair of the gauges,

Figure 2 is a side elevation of the gauge, 50

Figure 3 is a plan view of the gauge, and

Figure 4 is an end elevation of the gauge.

Ordinarily, in any printing press which prints direct from type, the setting of the inking rollers is accomplished by adjusting 55 the inking rollers into position against the ink table until the width of the impression on the ink table is about $\frac{1}{4}$ " in width and the entire length of the roller across the table. Repeated adjustments are made until the de- 60 sired impression is obtained. At best there is little accuracy in the method of adjusting the rollers due to the lack of precision gauges for determining the impression, since what is $\frac{1}{4}$ " to one man is $\frac{3}{8}$ " to another. The 65 guess work in setting and the resultant poor inking due to inaccurate setting is eliminated by the present invention.

Referring now to the accompanying drawing in which like characters of reference designate similar parts in the various views, 10 designates a type form, 11 the quoins, 12 the wood furniture, and 13 the type, these parts being of the usual and well known construction used in all printing presses which print 70 direct from type. As usual the form is placed on the bed of the press underneath the inking rollers which supply ink to the type. 75

In carrying out the invention I provide a 80 pair of gauges 14 which are adapted to be locked in the form with the type laterally of the type, as shown in Figure 1, and are used by the pressman to test the clearance between the inking rollers and the bed of the print- 85 ing press.

Each gauge 14 consists of a bar of suitable metal either solid or skeleton and preferably having opposite parallel sides 15 and a bottom 16 perpendicular to the sides whereby 90

the bar may be locked in the form with the type and be supported on the bed of the press in the same manner as the type. The top face of the bar is provided with a plurality of 5 steps 17 of different heights, the steps preferably increasing progressively in height from one end of the gauge to the opposite end thereof and each being parallel with the bottom 16 of the gauge. As best shown in Figure 3, each step is etched or otherwise provided with a corresponding numeral to indicate the height of the step, the numerals being preferably in thousandths of an inch. In the present embodiment the steps are graduated 10 in height and differ by .002 of an inch, the lowest step being preferably .900 of an inch in height and the highest step being .918 of an inch in height. An intermediate step will consequently be .910 and in practice the 15 best results are found when the inking rollers are set so that the clearance is .910 of an inch above the bed of the press, that is, .008 of an inch lower than the type. This marking of the gauge is by way of example only 20 since other desired markings may be employed.

In further carrying out the invention the stepped top face of the gauge is provided with a plurality of transversed grooves 18 which separate the steps or impression surfaces 17 and perform the twofold function of preventing ink from collecting in the corners between the steps and also defining the 25 steps one from the other so that the designating numerals thereof may be at all times clearly discernible. It is obvious that .002 of an inch is difficult to distinguish so that by defining the impression surfaces from each other by grooves they will be set off clearly 30 and distinctly so as to be easily identified.

In Figure 2, two positions of the inking roller 19 are shown and it will be observed, as indicated by the dot and dash line, that the clearance between the roller and the bed 45 of the press is sufficient to coincide with the impression surface marked .910 in Figure 3, consequently at this setting of the inking roller, the roller will be in accurate adjustment to properly ink the type for best results.

In operation, assume that the gauges 14 are locked in the form or chase approximately ten to fifteen picas from the edge of the form. Then remove all the rollers from the press except one. Place the form in the 55 press and clamp on to the bed. Put the press into motion and allow it to make two or three revolutions. Stop the press and inspect the gauges. Read the figure on the lowest step or impression surface that received ink. If the figure is .904, the roller is too low, and the necessary adjustments should be made to the journal box or bearing of the roller. If the figure is .916, the roller is too 60 high, and the adjustment should be changed to bring the roller down. Next wash off the

gauge and repeat the above operations until both gauges in the form register .910, that is, the impression surfaces so numbered are the lowest surfaces that receive ink. The roller now has the proper clearance above the bed of 70 the press. The adjusted roller is now numbered to identify its position and removed from the press whereupon the above operations are repeated for each roller in turn.

From the above description it is thought 75 that the construction and operation of my invention will be thoroughly understood without further explanation.

What is claimed is:

1. In a printing press, the combination 80 with a type form and an inking roller, of a stepped gauge in the form adapted to be engaged by the roller and indicate the impression of the roller on the type.

2. In a printing press, the combination 85 with a type form and an inking roller, of a tapered gauge locked in the form laterally of the type and having steps on the inclined top face adapted to be successively engaged by the roller to indicate the impression of 90 the roller on the type.

3. In a printing press, the combination 95 with a type form and an inking roller, of a gauge disposed in the form and having on the top face steps progressively increasing in height and adapted to engage the roller to 100 indicate the impression of the roller on the type.

4. In a printing press, a gauge for determining the impression of the inking roller, 105 comprising a bar adapted to be locked in the type form and provided with steps of different heights and bearing designating indices, there being transversed grooves in the bar separating the steps from each other. 110

5. A gauge for facilitating the adjusting of 115 a printing press roller to proper position for inking, comprising a bar having parallel sides and a bottom perpendicular to the sides whereby the bar may be locked in a type form with the type, the top face of the bar being stepped to provide impression surfaces of different heights adapted to engage the roller to indicate the setting of the roller, there being transversed grooves formed in the top 120 face of the bar performing the dual function of separating the steps so that they may be more readily distinguished one from the other and also preventing ink collecting in the corners between the surfaces.

6. In any printing press printing direct 125 from type, the combination with a cylindrical inking roller and a type form, of a stepped gauge locked in the form and adapted to engage the roller to indicate the clearance between the roller and the bed of the printing press.

7. In a printing press, a type form, a gauge 130 in the form laterally of the type and having a stepped top face providing impression sur-

faces for contact with the inking roller of the printing press, said surfaces being graduated in height and being provided with designating numerals, there being transversed grooves 5 in the top face of the gauge separating the surfaces and preventing ink from collecting in the corners between the surfaces, one of said surfaces being provided with numerals indicating the preferred clearance between 10 the inking roller and the bed of the printing press.

In testimony whereof I affix my signature.
